UNITED STATES PATENT OFFICE

EDWARD WALTER HOBBS, OF BALHAM, ENGLAND.

ARTIFICIAL ARM.

1,275,027.

Specification of Letters Patent. Patented Aug. 6, 1918.

Application filed March 6, 1918. Serial No. 220,790.

To all whom it may concern:

Be it known that I, EDWARD WALTER HOBBS, a subject of the King of England, residing in Balham, Surrey, England, have 5 invented certain new and useful Improvements in Artificial Arms, of which the following is a specification.

This invention is for improvements in or relating to artificial arms and has for its 10 object the provision of means which enable a wrist-bucket connected by side-irons to joints borne by the upper-arm sockets to receive a twisting movement about the axis of the fore-arm while the side-irons nevertheless maintain the connection of the 15 bucket with the elbow-joint pivots.

The invention is fully described with reference to the accompanying drawings in which—

20 Figure 1 is a side elevation of an artificial arm suitable for a low amputation; Fig. 2 is a plan of the same, and Fig. 3 is a detail end view of Fig. 2.

Like reference letters indicate like parts 25 throughout the drawings.

Referring to these drawings, there is illustrated a construction of artificial arm which is suitable for a patient who can twist the stump of his wrist or forearm, so that no 30 special mechanism is required for effecting the twisting of the wrist. In order to retain the usual forearm bucket B securely in position it is desirable that an upper arm socket A of the usual type should also be 35 used.

Two metal strips G, or a single strip suitably shaped, are secured along the sides of the bucket B, and they carry a plate G¹ which lies in a plane perpendicular to the 40 longitudinal axis of the forearm. Two tie-rods H are each provided with universal joints which preferably comprise spherical ends H¹, engaged in suitable sockets H² H³ provided respectively on a side-iron of the 45 upper-arm strap A, and on the strip G near the plate G¹ as shown. These rods H are stiff and inextensible and provide a secure but flexible connection between the wrist-plate G¹ and the upper-arm strap A. While 50 the rods are preferably stiff, they may be flexible enough to bend slightly over the patient's arm, when the wrist is twisted

from the position shown in Fig. 1 through a considerable angle, say 90°.

Conveniently there may be combined with 55 the plate G¹ fixed at the outer end of the wrist-bucket B a second plate G² for carrying an artificial hand or other device. This second plate G² is pivoted to the bucket-plate G¹ on a cross-axis transverse to the 60 axis of the forearm. It is also provided with a locking device preferably comprising a rigid arcuate lug G³ concentric with the cross-axis and notched as at G⁴. On the bucket-plate G¹ is a manually-controlled 65 latching lever G⁵ (Fig. 3) to engage the notches G⁴ of the arc G³ on the plate G² for the purpose of locking that plate and the artificial hand or attachment carried by it in any of the positions to which they may 70 be together adjusted about the cross-axis aforesaid.

A light spring G⁶ holds the lever G⁵ up against the lug G³, or in engagement with a notch G⁴. The plate G¹ is slotted at G⁷ to 75 permit the entry of the lug G³ when the plate G² is turned about the pivotal cross axis aforesaid.

What I claim as my invention and desire 80 to secure by Letters Patent is:—

1. In an artificial limb the combination with a plate secured on or at the outer end of a wrist-bucket or the like of stiff or slightly flexible side-irons that extend along opposite sides of the limb and, for the purpose described, are universally jointed (for example by ball-joints) to the plate and to a mounting on the patient's upper arm.

2. The combination with the subject-matter of preceding claiming-clause No. 1 of a 90 second plate for carrying an artificial hand or equivalent device, said plate being pivoted to the bucket-plate on a cross-axis transverse to the axis of the forearm and also provided with locking means to secure 95 it in any desired angular position about said axis (for example a rigid arc concentric with the cross-axis and notched, and a manually-controlled latching lever mounted on the bucket-plate for the purpose of engaging 100 the notches in said arc).

In testimony whereof I affix my signature.

EDWARD WALTER HOBBS.
